Primary Examiner — Ruth McInroy(74) *Attorney, Agent, or Firm* — Bernhard P. Molldrem, Jr.(57) **CLAIM**

We claim the ornamental design for a vacuum assisted dust collection hood for routers, as shown and described.

DESCRIPTION

FIG. 1 is a perspective view of a vacuum assisted dust collection hood for routers shown with a long chip cup, and showing our new design;

FIG. 2 is a top plan view thereof.

FIG. 3 is a right side elevation thereof, and showing the associated long chip cup.

FIG. 4 is a front elevation thereof.

FIG. 5 is a left side elevation thereof.

FIG. 6 is a rear elevation thereof.

FIG. 7 is a bottom plan view thereof.

FIG. 8 is a top plan view of a second embodiment thereof, shown with a short chip cup;

FIG. 9 is a right side elevation thereof.

FIG. 10 is a front elevation thereof.

FIG. 11 is a left side elevation thereof.

FIG. 12 is a rear elevation thereof; and,

FIG. 13 is a bottom plan view thereof.

The portion of the vacuum hose connector shown in broken lines forms no part of the claimed design.
